Specification for Design.

Patented May 8, 1917.

Application filed October 13, 1916. Serial No. 125,519. Term of patent 14 years.

To all whom it may concern:

Be it known that I, IHNA T. FRARY, a citizen of the United States, residing at 11328 Hessler road, Cleveland, in the county of Cuyahoga and State of Ohio, have invented a new, original, and ornamental Design for a Street-Light Standard, of which the following is a specification, reference being had to the accompanying drawing, forming part thereof.

Figure 1 is an elevation of a street light standard showing my new design.

Fig. 2 is a cross section through the fluted column of the standard.

I claim:

The ornamental design for a street light standard as shown.

In testimony whereof, I have hereunto set my hand in the presence of two subscribing witnesses.

IHNA T. FRARY.
